UNITED STATES PATENT OFFICE

DOMINGO ANTHONY USINA, OF NUTLEY, NEW JERSEY, ASSIGNOR TO MURRAY RADIATOR CORPORATION, OF BROOKLYN, NEW YORK, A CORPORATION OF NEW YORK

RADIATOR

Application filed December 18, 1929. Serial No. 414,855.

In a certain previous application Serial No. 294,191 filed July 20, 1928, there is described a radiator comprising a steam pipe or other heating element and an extended area structure applied thereto and fastened by certain supplemental fastening devices.

The present invention is directed to certain improvement in radiators of that general type. The accompanying drawings illustrate an embodiment of the invention.

Fig. 1 is a side elevation of an end of the radiator;

Fig. 2 is a horizontal cross-section thereof;

Fig. 3 is a vertical cross-section on the line 3—3 of Fig. 1;

Fig. 4 is an enlargement of a detail;

Fig. 5 is an enlarged section on the line 5—5 of Fig. 2.

The drawings illustrate the application to a steam pipe 1 of an extended structure comprising metal sheets corrugated to form laterally extending fins 2 which are slightly oblique, connected at their outer edges by longitudinal portions 3 and at their inner edges by longitudinal portions 4 which are bent outwardly at intervals to form recesses 5 embracing the pipe 1 between them. The corrugated plates are preferably of copper or aluminum or other metals of high heat conductivity. The pipe is preferably of copper or of other metal or alloy of comparatively high heat conductivity. For fastening the corrugated sheets on to the pipe longitudinally extending (that is, extending in the same direction as the heating element) straps or rods (preferably of steel) are used comprising inner portions 6 which bear against the portions 4 of the corrugated sheets and lateral portions 7 connected at their outer ends by longitudinal portions 8 embracing the outward corrugations of the sheets.

These straps are located close to the tube sections at points above and below the tube sections. The registering straps at opposite sides are then fastened together, preferably

by a welded joint indicated at 9, Fig. 4. The apparatus and method of producing such a welded joint are described more fully in a Phelps application Serial No. 305,652 filed September 13, 1928. They may be welded in other ways or may be fastened by other fastening means which will clamp the plates 4 closely into engagement with the pipe so as to provide and maintain a good heat conducting joint. Such a good contact is important particularly in this type of radiator where the corrugations provide vertical flues closed at the sides and open at the top and bottom and acting like chimneys to maintain a rapid circulation of air and to take away the heat very rapidly so that it must be supplied very rapidly from the steam pipe through the extended surfaces of the corrugated structure.

The same considerations apply with other types of extended heat radiating surface.

The straps preferably also bear against the outer faces of the corrugated sheets throughout their contour. They may in fact bear against such faces so closely as to slightly depress the sheets along the lines of engagement and thus lock the parts together more firmly. Such a construction is illustrated in Fig. 5 where the strap 8 fits in a depression 10 in the corrugated sheet. The depression 10 may be formed beforehand so as to provide a convenient locating means for the straps in assembling the parts, or they may be formed by the taking up of the straps in the welding operations as they are pressed together.

Straps passing entirely outside of the sheets are more easily applied than where they have to pass through openings in the sheets as in my previous application, above identified. Thus the assembling and the welding operations can be more economically performed. The straps of the present arrangement stiffen the radiator longitudinally and reinforce it against lateral bend-

ing. By bearing against the outer faces of the sheets, at several points in their length, they also stiffen the metal of such sheets. Their location beyond the outer faces of the sheets also protects the latter to a considerable extent against accidental injury. With the construction herein described the sheets may be of extremely thin gage.

Where straps of such size and material are used as to be sufficiently stiff, they will hold the parts together firmly without the necessity of welding them at all points, that is, between each pair of corrugations.

In special locations the extended area structures are different at opposite sides of the heating element, and in some cases such structure is applied to only one side. The straps of this invention may likewise be applied to only one side (combined with fastening means of a different type at the other side) or the straps may be of different designs to accommodate the designs of the sheets at opposite sides.

Various other modifications may be made by those skilled in the art without departing from the invention as defined in the appended claims.

What I claim is:

1. A radiator including in combination a heating element, an extended heat radiating surface structure in two parts applied to opposite sides of the heating element, and means for holding the two parts together comprising longitudinally extending straps

35 applied to the outer faces of said structure and lying entirely outside of and upon such outer faces, the straps at opposite sides of the radiator being united to each other.

2. A radiator including in combination a heating element, an extended heat radiating surface structure in two parts applied to opposite sides of the heating element, and means for holding the two parts together comprising longitudinally extending straps applied to the outer faces of said structure and lying entirely outside of and upon such outer faces, the straps at opposite sides bearing against the portions of said structure immediately adjacent to the heating element and welded to each other through said portions.

3. A radiator including in combination a heating element, a corrugated sheet metal structure in two parts applied to opposite sides of the heating element and longitudinally extending straps bearing against the outer faces of the corrugated sheets substantially throughout their periphery.

4. A radiator including in combination a heating element, a corrugated sheet metal structure in two parts applied to opposite sides of the heating element and longitudinally extending straps bearing against the outer faces of the corrugated sheets substantially throughout their periphery and lying in depression in said sheets.

5. A radiator including in combination a heating element, an extended heat radiating surface structure applied to the heating element, said structure comprising a plurality of lateral fins, and means for holding the parts together including a single longitudinally extending strap applied to the outer face of said structure and lying entirely outside of and upon said plurality of fins.

In witness whereof, I have hereunto signed my name.

DOMINGO ANTHONY USINA.
